Nathan Read. Belfast, Maine

Letter Patent

The Schedule referred to in the Letter Patent and making part of the same containing a description in the words of the said Nathan Read, him self, of his improvement in Rail Roads.

To all to whom these presents shall come, Be it known that I, Nathan Read of Belfast in the County of Maine and State of Maine have invented constructed and applied to a new and useful improvement in Rail Roads and that the following is, my description and specification of the construction and operation of my said improvement viz. I make a track resembling a strong ladder which I place between the rails of the road and connect with the road otherwise. This ladder or rack is constructed in the following manner. The two side pieces are made of square timber of any suitable kind of wood and of any convenient size, say 6 inches by ten square. These upon a suitable distance from each other lay from 5 to 10 inches. These two side pieces are connected together by stout bars of iron of a size sufficient to enter the side pieces sufficiently to give them permanence and strength and also to keep the side pieces at a proper distance from each other say 6 inches. These bars may be placed from 6 to 9 inches from each other so as to give sufficient room for the action of the long teeth of the cog wheel which is connected to the engine or locomotive which operates on the said road. This cog wheel is placed upon the shaft of the forward wheel of the locomotive or on any similar one may be placed upon the shaft of the hindmost wheel this wheel is placed midway between the wheels of the locomotive in such a position that its teeth pass in between the rooms of the rack & work against them when in operation. The wheel is made of a diameter sufficiently large to effect this. It is made very blunt, and its teeth larger than common. Object of this improvement is. The object of this improvement is the following viz. 1. To effect the proper action of the locomotive upon the road in the winter season in those climates where the earth may be covered with ice and

now and $8^{\frac{1}{2}}$ to effect its necessary Billy and elevations. During the winter in Northern climates. Rail Roads are liable to be clogged with snow covered with a crust of ice in such a manner as to greatly hinder or entirely prevent the progress of the Locomotive on the Rails. To prevent the danger of the Locomotive being thrown from the Rail by retardation in its progress. the ladder rack is used being laid & fastened firmly upon the sills or foundation of the other rails. and the work being open or in other words the rods somewhat distant from each other. the long teeth of the wheel above described will pass effectually between them & thereby give a hold firm hold as to enable the locomotive to progress with its usual strength & speed. In addition to placing the ladder rack midway between the rails. I attach sometimes when necessary ladder racks on each side of the road. the rails making one end of the ladder when the rods are attached to the rails. it may not always be necessary to have but one side of the ladder and that side may be the rail & the teeth will then project in towards the centre of the road in bends or turns in the road the rods may be only on one side of the road. Reference to the Plates. — Plate 1st Represents the rail road with the ladder rack in the middle a. a. the sills of the road b. b. the rods of the road c. c. the ladder rack in its place in the road. Plate 2nd Fig 1. Represents the long toothed wheel which is to pass or fit in between the rods of the ladder rack. Fig 2. is a representation of the Locomotive in action — Claiming — What I claim specifically claiming my improvement and particular and exclusive right is. 1st My mode of constructing a ladder rack and the applying of it to rail Roads & Locomotives above described. 2. The application of a wheel as above described having longer teeth than have hitherto been used on locomotives. Testimony that the above is a true specification of my said improvement as above described I have here set my hand this 31st day of January 1836.
